DESIGN FOR A NECKTIE CLIP OR SIMILAR ARTICLE

Joseph Carlton Bagnall, Attleboro, Mass., assignor to The Baer & Wilde Company, Attleboro, Mass., a corporation of Massachusetts

Application October 7, 1933, Serial No. 49,417

Term of patent 3½ years

To all whom it may concern:

Be it known that I, JOSEPH CARLTON BAGNALL, a citizen of the United States of America, residing in Attleboro, in the county of Bristol and Commonwealth of Massachusetts, have invented a new, original, and ornamental Design for a Necktie Clip or Similar Article, of which the following is a specification, reference being had to the accompanying drawing, forming a part thereof.

The figure is a face view of a necktie clip showing my new design.

I claim:

The ornamental design for a necktie clip or similar article as shown.

Signed by me at Attleboro, in the county of Bristol and Commonwealth of Massachusetts, this 5th day of October, 1933.

J. CARLTON BAGNALL.
